UNITED STATES PATENT OFFICE

JOSEPH L. DOSTAL, OF DETROIT, MICHIGAN, ASSIGNOR TO EARL HOLLEY, OF DETROIT, MICHIGAN

CAST-IRON MOLD

Application filed September 12, 1927, Serial No. 218,884. Renewed August 1, 1929.

The object of this invention is to design a mold suitable for use in the radiator molding machine described in the co-pending application, Serial No. 218,883, filed September 5 12, 1927, of which I am one of the joint inventors.

Figure 1 shows the mold in elevation.

Figure 2 shows a cross section on the plane 2—2 of Figure 1, with a radiator casting 10 shown in elevation.

The molds are arranged back to back, so that each mold contains two similar matrices or depressions, each depression being adapted to form half of a casting of one radiator section. The molds are adapted to be poured with the parting line in the vertical plane, and the mold inclined 30° to the position shown in the drawing.

In the figures, A is the gate. B is the matrix of the mold. C D are the core supports. The corresponding core supports on the right hand side are concealed by the casting shown in place. These core supports are perforated. E is the riser, which, when the mold 25 is inclined 30°, is slightly below the top of the gate A. The purpose of this is to prevent the molds locking together, the riser E acting as a drain to remove any superfluous metal.

F G are the dowel pins, which enable the molds to be aligned together. H is the pin for moving the molds, the complete mechanism, of which this is a part, being disclosed in the co-pending application referred to. J 30 is an arm extending from the mold to form a support, which is also described in detail in the co-pending application referred to.

In Figure 2 the casting is shown in place, together with the sprue. The interior of the 40 mold is hollow, and is open at the sides and bottom so that the gases generated within the core escape freely through C D into the interior of the mold and so to the atmosphere.

What I claim is:

45 1. In a double faced hollow radiator mold with the parting line substantially in the vertical plane, a perforated core support whereby the gases generated within the cores are vented to the interior of the hollow mold.

50 2. A double faced hollow metal mold

adapted to mold hollow metal castings, a perforated core support whereby the gases generated within the cores are vented to the interior of the hollow mold.

In testimony whereof I affix my signature. 55
JOSEPH L. DOSTAL.
